By Thomas A. Jenkins Jr.

Attorney

UNITED STATES PATENT OFFICE

PAUL J. BELLAVANCE, OF ATTLEBORO, MASSACHUSETTS

PENHOLDER

Application filed May 14, 1929. Serial No. 362,979.

My invention relates to universal mountings, particularly of a type adapted to hold a fountain pen in a suitable base.

An object of my invention is to provide a universal mounting of this type having a portion thereof rotatable in a horizontal plane, movable means to frictionally engage the rotatable portion of said mounting to limit the free rotational movement thereof, means mounted on said rotational means pivotable in a vertical plane and adapted to have the pen holder attached thereto to pivot therewith and movable means to limit the pivotal movement of said pen holder and pivotable means. I thus provide a universal mounting for said pen holder in which the universal movement thereof may be readily limited as the parts thereof wear down in use, a feature I believe novel to universal mountings for pen holders of this type.

A further object of my invention is to provide a universal mounting relatively cheap, strong, easy to construct and which will always stay in the desired set position.

These and such other objects of my invention as may hereinafter appear will be best understood from a description of the accompanying drawings, which illustrate an embodiment thereof.

In the drawings, Fig. 1 is a perspective view of my improved mounting mounted on a suitable base, a fountain pen in the holder thereof being shown in dotted lines.

Fig. 2 is a sectional view through the mounting and base, the pen holder being shown in elevation.

Fig. 3 is a detached front elevation partly in section of the rotatable member of my mounting and the parts carried thereby.

In the drawings, wherein like characters of reference indicate like parts throughout, 10 generally indicates a suitable base which may be constructed of onyx stone, celluloid or other suitable material and is adapted to rest on a suitable surface 12 such as a top of a table. While my improved universal mounting 14 for the pen holder 16 may be mounted on said base in any suitable manner I preferably provide the base 10 with the well 18. I also preferably provide a hole

20 extending from the lower end of said well 18 to the bottom of the base 10 in my preferred embodiment to the inset 22. As stated, I preferably provide a universal mounting of a type wherein a portion thereof adapted 55 to contain the pen holder is pivotable in a vertical plane. In my preferred embodiment, I preferably construct my improved universal mounting as follows: I provide a suitable retaining cap member 24 having an outer 60 wall 26 of a configuration to be inlaid in said well 18, an internally threaded inner circular wall 28 and a top wall 30 extending radially inwards a substantial distance thereof to form a central hole 32. For the rotatable 65 member of my improved universal mounting I provide the circular plate 34 of a larger diameter than said hole 32 in said cap member 24. Said rotatable plate 34 is preferably provided with the two spaced pivot ears 36 70 having the transverse holes 38 therein upstanding therefrom through said hole 32 in said cap member 24. I provide the pivot bar 40 rigidly mounted in said transverse holes in any suitable fashion, such as by the 75 pin 41. As the portion of my improved pivotal mounting pivotal in a vertical plane, I provide the collar 42 having the central hole 44 therein for pivotal mounting on said bar 40 between said ears 36 having an extension 80 45 projecting radially upwards therefrom having an internally threaded bore 46. For a purpose to be described, I provide the solder 48, soft metal, Babbitt metal or other resilient substance in the lower portion of said bore 85 46 adjacent the pivot bar 40 to limit the free pivotal movement of said collar 42. As a pen holding device 16 I provide a pen holding tube 50 having a tapered lower end 52 externally threaded as at 54 threadedly retained in the upper portion of said collar extension bore 46. It is thus obvious that by screwing the fountain pen holder down within said threaded bore 46 that it will force the solder 48 against the pivot bar 40 to limit the free 90 pivotal movement of said collar 42 and pen holder 50. The pen holder 50 is hollow and is adapted to receive therein a fountain or other pen 56 as shown in Fig. 1. It is thus obvious that I have provided a universal 95 100

mounting having a portion pivotal in a plane at right angles to the base thereof with movable means therein to limit the free pivotal movement of said portion.

5 To limit the free rotational movement of the rotatable plate 34 I preferably provide the locking plate 62 externally threaded as at 64 and provided with the central hole 66 therein and threadedly engage the exterior 10 threaded surface 64 thereof within the lower portion of the threaded circular wall 28 of said cap member. Said locking plate 62 is provided with suitable means such as the diametrically opposite holes 68 therein to 15 turn it. Said locking plate 62 is also provided with the upstanding outer top edges 70 adapted to bear against the lower surface of said rotatable plate 34 to limit the free rotatable movement thereof within said cap 20 member 24 on upward rotation of said locking plate within the threaded interior of said cap member. It is thus apparent that I have provided a universal mounting having a suitable rotatable plate freely rotatably mounted 25 within said mounting and movable means such as the locking plate 62 to limit the free rotational movement of said rotatable plate.

As stated my improved universal mounting is preferably inset within the well 18 of 30 the base 10 preferably so as to be flush therewith and suitably secured within said hole to the base member 10. In my improved embodiment for this purpose I preferably provide bolt means extending through said hole 35 66 in the locking plate and said hole 20 in said base to rigidly secure said mounting to said base, which in my improved embodiment comprises the bolt 72 projecting downwards through said hole 66 and hole 20 into the 40 inset 22 in the bottom of the base and the nut 74 threaded on to the lower end of said bolt.

It is thus obvious that I provide a novel type of universal mounting particularly adapted for pen holders which includes a 45 member rotatable in one plane and a portion pivotal in a plane at right angles thereto on which the pen holder 50 is mounted and suitable movable means in said mounting to increase the friction against the rotatable 50 member and pivoting means to limit the free respective rotation and pivotal movement thereof with the advantages described above.

It is understood that my invention is not limited to the specific embodiment shown and 55 that various deviations may be made therefrom without departing from the spirit and scope of the appended claims.

What I claim is:

1. A pen holder, comprising a base having 60 a well therein said well having a hole extending to the bottom of said base, a universal mounting comprising a retaining cap member having an outer wall of a configuration to be inlaid in said well, an internally 65 threaded circular inner wall and a top wall

extending radially inwardly a substantial distance thereof providing a central hole, a rotatable plate of a larger diameter than said hole in said cup member having pivot ears having transverse holes therein upstanding therefrom through said hole in said cap member, a pivot bar rigidly mounted in said transverse holes, a collar pivotally mounted on said bar between said ears having an extension projecting radially upward therefrom having a threaded bore, solder means contained in the lower portion of said bore adjacent the pivot bar to retard the pivotal movement of said collar, a pen holding tube having a tapered externally threaded lower end threadedly contained in the upper portion of said collar extension bore whereby screwing down of said pen holding tube may force the solder against the pivot bar to retard the free pivotal movement of said collar and pen holder, an externally threaded locking plate having a central hole therein threadedly engaged in the lower portion of the threaded circular inner wall of said cap member having means to turn it and upstanding outer top edges adapted to bear against said rotatable plate to retard the free rotational movement of said plate within said cap member on upward rotation of said locking plate and bolt means extending through said hole in said locking plate and hole in said base to rigidly secure said universal mounting to said base.

2. A pen holder, comprising a base having a well therein said well having a hole extending to the bottom of said base, a universal mounting comprising a retaining cap member having an outer wall of a configuration to be inlaid in said well, an internally threaded circular inner wall and a top wall extending radially inwardly a substantial distance thereof providing a central hole, a rotatable plate of a larger diameter than said hole in said cap member having pivot ears having transverse holes therein upstanding therefrom through said hole in said cap member, a collar pivotally mounted between said ears having an extension projecting radially upward therefrom having a threaded bore, a pen holding tube having a tapered externally threaded lower end threadedly contained in said collar extension bore, an externally threaded locking plate having a central hole therein threadedly engaged in the lower portion of the threaded circular wall of said cap member having means to turn it and upstanding outer top edges adapted to bear against said plate to retard the free rotational movement of said plate within said cap member on upward rotation of said locking plate and bolt means extending through said hole in said locking plate and hole in said base to rigidly secure said universal mounting to said base.

3. A universal mounting comprising a re-

- taining cap member having an internally threaded circular inner wall and a top wall extending radially inwardly a substantial distance thereof providing a central hole, a 5 rotatable plate of a larger diameter than said hole in said cap member having pivot ears having transverse holes therein upstanding therefrom through said holes in said cap member, a pivot bar rigidly mounted in said 10 transverse holes, a collar pivotally mounted on said bar between said ears having an extension projecting radially upward therefrom having a threaded bore, soft metal contained in the lower portion of said bore adjacent the pivot bar to retard the pivotal movement of said collar, a pen holding tube 15 having a tapered externally threaded lower end threadedly contained in the upper portion of said collar extension bore, whereby screwing down of said pen holding tube may force the soft metal against the pivot bar to retard the free pivotal movement of said collar and pen holder, an externally threaded locking plate threadedly engaged in the lower portion of the threaded circular wall of said 20 cap member having means to turn it and upstanding outer top edges adapted to bear against said plate to retard the free rotational movement of said plate within said cap member on upward rotation of said locking plate and bolt 25 means extending through said hole in said locking plate and hole in said base to rigidly secure said universal mounting to said base.
4. A universal mounting comprising a retaining cap member having an internally threaded circular inner wall and a top wall extending radially inwardly a substantial distance thereof providing a central hole, a plate of a larger diameter than said cap member having pivot ears having transverse holes therein upstanding therefrom through said hole in said cap member, a 30 collar pivotally mounted between said ears having an internally threaded bore, a pen holding tube having a tapered externally threaded lower end threadedly contained in said collar extension bore, an externally threaded locking plate threadedly engaged in the lower portion of the threaded circular wall of said cap member having means to turn it and upstanding outer top edges adapted to bear against said plate to retard the free rotational movement of said plate within said cap member on upward rotation of said locking plate.
5. A pen holder, comprising; a member having pivot ears upstanding therefrom having transverse holes therein, a pivot bar rigidly mounted in said transverse holes, a collar pivotally mounted on said bar between said ears having an extension projecting radially upwards therefrom having an internally threaded bore, soft metal contained in the lower portion of said bore adjacent the pivot bar to retard the pivotal movement of said collar, a pen holder tube having an externally threaded lower end threadedly contained in the upper portion of said collar ex-
- tension bore, whereby screwing down of said pen holding tube may force the soft metal against the pivot bar to retard the free pivotal movement of said collar and pen holder. 70
6. A pen holder, comprising a base having a well said well having a hole extending to the bottom of said base, a universal mounting comprising a retaining cap member having an outer wall of a configuration to be inlaid in said well, an internally threaded circular inner wall and a top wall extending radially inwardly a substantial distance thereof providing a central hole, a rotatable plate of a larger diameter than said hole in said cap member, a pen holder pivotally mounted on said plate in a plane at right angles to said plate, an externally threaded locking plate having a central hole therein threadedly engaged in the lower portion of the threaded circular wall of said cap member having means to turn it and upstanding outer top edges adapted to bear against said plate to retard the free rotational movement of said plate within said cap member on upward rotation of said locking plate and bolt 80 means extending through said hole in said locking plate and hole in said base to rigidly secure said universal mounting to said base. 85
7. A pen holder, comprising, a base having a well therein and a universal mounting rigidly inset in said well comprising a plate rotatably mounted within said mounting, movable means in said mounting to frictionally bear against said plate to retard the rotational movement thereof, mounting means including a portion rigidly mounted on said plate to rotate therewith, and a portion pivotal on said rigid portion in a plane at right angles to said plate, a pen holder mounted on said pivotal portion and movable means to frictionally bear against said rigidly mounted portion to retard the pivotal movement of said pen holder and pivotable portion. 90
8. A universal mounting, comprising a plate rotatably mounted within said mounting, movable means in said mounting to frictionally bear against said plate to retard the rotational movement thereof, mounting means including a portion rigidly mounted on said plate to rotate therewith, and a portion pivotal on said rigid portion in a plane at right angles to said plate, a pen holder mounted on said pivotal portion and movable means to frictionally bear against said rigidly mounted portion to retard the pivotal movement of said pen holder and pivotable portion. 105
9. In combination, a stationary member, a member pivotally mounted on said stationary member, one of said members having a threaded hole extending through it to the other member, soft metal contained within the base of said hole adjacent the other member and screw means adapted to be threaded down said hole to force said soft metal 110
- 120
- 125
- 130

against said other member to retard the pivotable movement of said pivotable member.

10. In combination, a stationary member, a member pivotally mounted on said stationary member, having a threaded hole extending through it to the stationary member, soft metal contained within the base of said hole adjacent the stationary member and screw means adapted to be threaded down 10 said hole to force said soft metal against said stationary member to retard the pivotable movement of said pivotable member.

In testimony whereof I affix my signature.

PAUL J. BELLAVANCE.
